SINGLE POINT RELEASE FOR PARACHUTE HARNESS

Lawrence M. Johnston, Indianapolis, Ind., assignor to himself, as trustee

Application December 15, 1944, Serial No. 568,256

12 Claims. (Cl. 24—205)

1

The present invention relates to connectors for parachute harness, and its primary object is to provide a simple, inexpensive, fool proof means for holding the ends of the various straps of a parachutist's harness, which means will nevertheless be readily and quickly actuatable to release all of said straps, whereby the parachutist may instantly divest himself of the harness. Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, so long as the scope of the appended claims is not violated.

Fig. 1 is a plan of my connector, parts being broken away for clarity of illustration;

Fig. 2 is a similar view, the operating disc having been removed;

Fig. 3 is a vertical section through the connector, taken substantially on the line 3—3 of Fig. 4, and looking in the direction of the arrows;

Fig. 4 is a transverse section through the connector, taken substantially on the line 4—4 of Fig. 3, and looking in the direction of the arrows;

Fig. 5 is a fragmental section taken substantially on the line 5—5 of Fig. 1 and looking in the direction of the arrows;

Fig. 6 is a fragmental section taken in the plane of Fig. 3 and showing the latch pawl in release position; and

Fig. 7 is a similar section showing the parts in an intermediate position during engagement of a buckle with a hook and pawl.

Referring more particularly to the drawing, it will be seen that I have illustrated a connector unit which comprises a base element 10 to the under surface of which is secured a pad 11 which may preferably be made of leather. The base member 10 is formed to provide a plurality of perimetrically spaced, upstanding hooks 12, 12', 12'', and 12'''.

While four such hooks are illustrated in the present drawing, together with four of each of the parts cooperating with said hooks, it will of course be understood that any suitable number of hook assemblies may be provided, depending upon the particular harness selected for use. Obviously, one hook will be provided for each harness buckle. The base member 10 may further be provided with an eye 13 to which may be per-

2

manently connected a lanyard attached to the harness, so that the connector will not be lost when the harness buckles 14 are disconnected therefrom.

5 The base member 10 is centrally perforated as at 15 to provide a journal mounting for a rotary stem 16 which carries cam means, indicated generally by the reference numeral 17. Said cam means is formed to provide a plurality of cam 10 risers, one for each hook assembly, and indicated generally by the reference numerals 18, 18', 18'', and 18'''', disposed generally in a plane normal to the axis of the stem 16, and radiating from said axis. The riser 18 is formed at one end with 15 a high portion 18a, and inclined downwardly toward the base element 10 to a low portion at its opposite end 18b. Adjacent the end 18b of the riser 18, the same is notched or mutilated, as at 19, for a purpose later to be described. Similarly, 20 the riser 18' declines from its high point 18'a to its low point 18'b which is immediately adjacent a notch 19'; the riser 18'' declines from its high point 18''a to its low point 18''b which is immediately adjacent a notch 19''; and the riser 25 18''' declines from its high point 18'''a to its low point 18'''b which is immediately adjacent a notch 19'''.

The upstanding perimetral wall 10' of the base element 10 is provided with a plurality of perimetrically spaced bores 20 which are internally threaded at their lower ends for the reception of screws 21 whereby the pad 11 is secured to the base element, and for the reception of oppositely-entered screws 22 which penetrate bores formed 30 in a corresponding perimetral wall of a housing element 23, said latter perimetral wall registering with said upstanding wall 10' and preferably, though not necessarily, being rabbeted at 24 to cooperate with the cooperatively formed upper 35 edge of said wall 10'.

The uppermost surface of the housing element 23 is dished, as at 25, for a reason which will appear, and is centrally formed with a downwardly projecting hub 26 providing a journal support 27 45 for the stem 16. At peripherally spaced points, said hub 26 is formed with four downwardly-opening slots 28, etc., and said slots, and their bounding walls, are traversed by bores 29 in which may be mounted pivot pins 31, all as is clearly illustrated in Figs. 3, 4, and 5. The uppermost wall of each of said slots is further provided with a tapped bore 30 for a purpose later to become apparent.

Pivotedly mounted upon each pivot pin is a pawl latch, said latches being indicated by the reference numerals 32, 32', 32'', and 32'''.

Since these

four latch assemblies are identical, only one has been illustrated in detail, and only one will be described.

The latch pawl 32 is provided at its outer end with a radially opening socket 33, the outermost boundary of which is defined by an outwardly and upwardly inclined surface 34. The cam surface 34 is so proportioned and designed that its outermost point is spaced beyond the uppermost surface 37 of the hook 12 by a distance greater than the radius of the end portion of the bar forming the buckle 14, for a reason which will appear hereinafter.

Facing inwardly, the latch pawl 32 is formed with a notch 35 receiving and snugly embracing the cam riser 18. When the latch pawl 32 is in its lowermost position, as illustrated in Fig. 3, the socket 33 faces, and is guarded by, the inwardly presented face 36 of the hook 12, so that, so long as the latch 32 is retained in the position of Fig. 3, the buckle 14 cannot possibly escape from its imprisonment between the hook surface 36 and the pawl socket 33.

A screw 38, received in the bore 30, anchors one end of a leaf spring 39, the free end of which bears upon the upper surface of the pawl 32, biasing said pawl toward its position illustrated in Fig. 3. So long as the cam riser 18 is engaged in the pawl notch 35, the position of the pawl is entirely controlled by the position of the cam 17.

An operating disc 40 has its hub 41 received upon, and secured to, the outer end of the stem 16, by means of a screw 42, or the like; and it will be obvious that the cam 17 is actuatable by said disc 40.

A socket 44 formed in the perimetral wall of the housing element 23, reciprocably receives a plunger 45 which is urged, by a spring 46, outwardly into engagement with the operating disc 40. In its under surface, the disc 40 is formed with a peripherally extending channel 47; and it will be obvious that the engagement of the plunger 45 in said channel 47 limits the throw of the operating disc 40. When the disc is in the position illustrated in Fig. 1, the cam 17 is in the position illustrated in Fig. 3, holding the pawls 32, etc., in their positions firmly retaining the buckles 14 against the hooks 12, etc. The disc is provided, at a suitable point, with a radially extending bore 49 which, when the parts are in the above-mentioned positions, registers with a socket 50 formed in the housing element 32; and a pin 51 is removably received in said bore 49 and socket 50 to hold the parts in locked-up position.

When the pin 51 is withdrawn, the disc 40 may be turned, in a clockwise direction as viewed in Fig. 1, until the right-hand end of the channel 47 engages the plunger 45. That degree of rotation of the disc 40 will shift the cam 17 from its position illustrated in Fig. 3 to its position illustrated in Fig. 6, thereby lifting all of the pawls 32, etc., to shift the sockets 33 thereof into positions in which they are not guarded by the hooks 12, etc. Thus, instantaneously, all of the buckles 14 are released from the connector, and the harness will drop off the parachutist's torso instantaneously.

To reassemble the organization, it will be clear that it would be possible, with the assistance of one or two other men, to move the four buckles into the sockets 33 of the pawls 32, etc., and, holding the buckles in positions like that illustrated in Fig. 6, to return the disc 40, in a counter-clockwise direction, to the position of Fig. 1, thereby camming the pawls into the position

illustrated in Fig. 3. Such an operation, however, would be extremely difficult for an unassisted operator. It will be noted that the channel 47 is shown, in Fig. 1, to have a clockwise extension 52 beyond the position occupied by the plunger 45 in Fig. 1. That extension 52 is somewhat shallower than the main body of the channel 47. Therefore, when the disc 40 is returned from its release position, it will be brought to a stop at the point at which the bore 49 and the socket 50 register. If, now, the end of the pin 51 is pushed through the hole 48 in the disc 40 to depress the plunger 45 somewhat against the tendency of the spring 46, the counter-clockwise movement of the disc 40 can be continued until the extremity of the channel extension 52 engages the plunger 45.

Such further movement of the disc 40 will shift the low points 18b, etc., of the risers 18, etc., beyond the points of engagement in the notches 35 of the pawls 32, etc., and bring the notches 19, etc., into registry with the pawls. Now, the pawls are free from control by the cam, and are held in their lowermost positions only by the resilient effect of the springs 39. Since the outermost points of the cam noses 34 of the pawls 32, etc., are spaced from the surfaces 37 of the hooks 12, etc., by a distance greater than the radius of the buckle bar 14, it will be seen that, if such buckle bar 14 is moved across the surface 37, it will engage the cam nose 34 in such a fashion as to cam the pawl 32 upwardly, in the manner illustrated in Fig. 7. Continued movement of the buckle will force the pawl far enough upwardly to permit the buckle to be entered in the socket 33, whereupon the spring 39 will snap the pawl downwardly into the position shown in Fig. 3. It will be clear that the portion of the pawl below the notch 35 will, during this operation, move upwardly and then downwardly through the notch 19.

After all four buckles have been assembled with the connector in the above described manner, the disc 40 will be turned, in a clockwise direction, until the plunger 45 snaps back into the deeper portion of the channel 47. At this point, the bore 49 and the socket 50 will register, and the pin 51 can be inserted thereinto to lock the parts in buckle-retaining positions.

As will be clear from an inspection of the drawing, the peripheral walls of the base element 10 and of the housing element 23 are slotted, as at 23, for instance, to permit the projection therethrough of the pawls 32, etc.; and preferably those notches will closely fit the lateral dimensions of the pawls in order to support said pawls laterally, in the manner clearly shown in Fig. 2.

I claim as my invention:

1. A connector for parachute harness comprising a housing, a plurality of pawls mounted in said housing upon stationary pivots and having their free ends located at spaced points about the perimeter of said housing, cam means rotatably mounted in said housing and engaging all of said pawls for positively moving said pawls concurrently in either of two opposite directions about their respective pivots, and means for positively locking said cam means against movement.

2. A connector for parachute harness comprising a plurality of hooks peripherally spaced about a common axis, each adapted to be engaged by an element of a harness, a plurality of pawls, each associated with one of said hooks and movable

into and out of position to engage such harness element and hold the same against disengagement from its hook, a member journalled for movement about said common axis, and cam means movable with said member and engaging all of said pawls to move said pawls positively and concurrently into and out of such engaging position.

3. A connector for parachute harness comprising a plurality of hooks peripherally spaced about a common axis, each adapted to be engaged by an element of a harness, a plurality of pawls, each associated with one of said hooks and movable into and out of position to engage such harness element and hold the same against disengagement from its hook, a member journalled for movement about said common axis, means for locking said member against such movement, and cam means movable with said member and engaging all of said pawls to move said pawls positively and concurrently into and out of such engaging position.

4. A connector for parachute harness comprising a housing, a plurality of pawls mounted in said housing upon stationary pivots and having their free ends located at spaced points about the perimeter of said housing, cam means rotatably mounted in said housing and engaging all of said pawls for positively moving said pawls concurrently in either of two opposite directions about their respective pivots, means for positively locking said cam means against movement, said cam means being mutilated to provide portions clearing said pawls, and releasable means normally limiting movement of said cam means to prevent registration of said clearing portions with said pawls.

5. A connector for parachute harness comprising a plurality of hooks peripherally spaced about a common axis, each adapted to be engaged by an element of a harness, a plurality of pawls, each associated with one of said hooks and movable into and out of position to engage such harness element and hold the same against disengagement from its hook, a member journalled for movement about said common axis, and cam means movable with said member and engaging all of said pawls to move said pawls positively and concurrently into and out of such engaging position, said cam means being mutilated to provide portions clearing said pawls, and releasable means normally limiting movement of said cam means to prevent registration of said clearing portions with said pawls.

6. A connector for parachute harness comprising a base element providing a plurality of hooks peripherally spaced about a common axis, cam means journalled in said base element upon said axis, a housing element fixed to said base element and providing a journal mounting for said cam means, said housing element further providing pivotal mountings for a plurality of pawls, each arranged for cooperation with one of said hooks, said cam means being operatively associated with said pawls to shift the same positively into and out of locking relationship with their respective hooks, and operating means for such cam means located outside said housing element and operatively connected to said cam means.

7. A connector for parachute harness comprising a plurality of hooks radiating from a common axis and each adapted to be engaged by a harness element, a corresponding number of pawls

radiating from said axis in cooperative relation with said respective hooks and mounted for oscillation about separate axes all located in a plane normal to said common axis, and cam means oscillable about said common axis and formed to provide a plurality of peripherally-spaced identical cam risers, one for each of said pawls, each pawl being formed with a notch opening toward its pivotal axis and receiving one of said cam risers, and each pawl, at one extremity of its path of movement, being adapted to engage a harness element engaging its associated hook to prevent disengagement thereof.

8. The structure recited in claim 7 in which the cam means is mutilated, at one extremity of each cam riser, to provide a portion clearing its pawl, in which spring means cooperates with each pawl to urge the same toward retaining relation with its hook when said clearing portion of the cam means registers with such pawl, and in which each pawl is provided with a camming nose engageable by a harness element, when said clearing portion of the cam means registers with such pawl, to shift such pawl temporarily out of retaining relation with its hook against the tendency of its spring means.

9. In a device of the class described, a base providing a plurality of perimetrlly spaced upstanding hooks, a pawl for each of said hooks, each pawl being formed with an outwardly-opening socket and being mounted to swing into and out of a position in which its socket faces and is guarded by the inwardly-presented face of its hook, and cam means journalled on said base and engaging all of said pawls, said cam means being movable in opposite directions to shift said pawls positively and concurrently into and out of such position.

10. In a device of the class described, a base providing a plurality of perimetrlly spaced upstanding hooks, a pawl for each of said hooks, each pawl being formed with an outwardly-opening socket and being mounted to swing into and out of a position in which its socket faces and is guarded by the inwardly-presented face of its hook, the outermost boundary of said socket being inclined outwardly and away from said socket, and lying, when said pawl is in such position, beyond the end surface of its hook, and resilient means normally holding said pawls in such positions.

11. In a device of the class described, a base providing a plurality of perimetrlly spaced upstanding hooks, a pawl for each of said hooks, each pawl being formed with an outwardly-opening socket and being mounted to swing into and out of a position in which its socket faces and is guarded by the inwardly-presented face of its hook, and cam means journalled on said base and operatively engaging all of said pawls to shift the same positively and concurrently in either of two opposite directions, said pawls, in one position of said cam means being positively held with their sockets positioned beyond the outermost ends of their hooks, in another position of said cam means being positively held with their sockets guarded by said hooks, and in another position of said cam means being free from said cam means, the outermost boundary of each of said pawl sockets being inclined outwardly and away from said socket and lying, when said socket is guarded by its hook, beyond said outermost end of said hook, and resilient means normally holding said pawls in socket-guarded position.

12. In a device of the class described, a base providing a plurality of perimetrally spaced up-standing hooks, a stem journalled in said base equidistant from said hooks, a plurality of cam members, one for each of said hooks, radiating from said stem, a housing member fixed to said base, overlying said cam members, and providing a journal support for said stem, a plurality of pawls, one for each hook, mounted on pivotal axes which are carried by said housing member and which lie in a common plane normal to the

axis of said stem, said housing being formed with a plurality of peripherally-opening slots through each of which one of said pawls projects into cooperative relation with its hook, operating means outside said housing member fixed to said stem, each of said cam members having a positive, two-way operative connection with one of said pawls, and means for preventing inadvertent movement of said operating means.

LAWRENCE M. JOHNSTON.
